UNITED STATES PATENT OFFICE.

HAROLD W. NICHOLS, OF MAPLEWOOD, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed August 31, 1922. Serial No. 585,356.

This invention relates to signaling systems and particularly to apparatus for use in connection with the high speed signaling systems, such as telegraph systems.

- 5 An object of the invention is the provision of means responsive to line current changes for producing in a local circuit a uni-directional current irrespective of the polarity of the line current impulses.
- 10 In accordance with the above and other objects, the present invention provides a pair of magnetically controlled devices responsive to line current changes for producing in a local circuit including auxiliary controlled means a uni-directional polarizing current irrespective of the polarity of the line current impulse. Specifically, the invention provides a normally unpolarized relay having an operating winding and magnetizing windings to control its operation.
- 15

In order to permit the operation of the relay in conjunction with a low impedance signaling circuit over which it is desirable to transmit the signaling impulses at an extremely high speed, the magnetizing windings are connected in circuit with a pair of magnetically controlled vacuum tubes. Each tube consists of an evacuated envelope containing an electron emitting cathode and an anode, and provided with means for generating a magnetic field, which normally prevents or reduces to a low value the current between the cathode and anode. Each tube is provided with a control magnetizing winding connected to receive current from the signaling conductor over which the impulses are to be transmitted. The control windings are oppositely connected to the line and respond to current changes of opposite polarity for permitting cathode anode current to flow through the magnetizing windings of the relay. The current through the magnetizing windings will be in the same direction irrespective of the character of the impulse impressed on the operating winding. The operating winding of the relay is connected in series with the line and the armature is attracted to one or the other of the poles according to the polarity of the signals. This provides a very sensitive relay arrangement readily adaptable to low impedance circuits.

Referring to the drawing,

Fig. 1 illustrates schematically one embodiment of the invention;

Fig. 2 shows the type of vacuum tube employed.

In Fig. 1 there is shown a relay having a soft iron magnetic core 6, which has pole pieces 7 and 8 supporting magnetizing windings 9 and 10. These magnetizing windings 9 and 10 are connected in series. Pivoted on a projecting portion of the magnetic core 6 is an armature 11 adapted to swing between the pole pieces 7 and 8. In order that the armature 11 will, after each operation, be restored to its central or neutral position, a retractile spring 12 is connected to one end of armature 11. Operating winding 13 is adapted to magnetize the armature 11 so that it may be attracted by either pole piece 7 or 8 depending upon its polarity.

In the drawing, like parts of the vacuum tubes are represented by the same reference characters with the prime indices added. Connected in circuit with the magnetizing windings 9 and 10 are two vacuum tubes 14 and 15. Each of these tubes comprises an elongated glass vessel containing an electron emitting cathode 16, which is supplied with current by a battery 23, and a cylindrical anode 20. Each of the tubes is provided with a pair of magnetic coils 22 and 25, which encircle the glass vessel for generating a magnetic field thereby controlling the flow of current between the cathode 16 and the anode 20. The coil 22 of tube 14 and coil 22' of tube 15 are supplied with current from a battery 24 for providing a constant flux through these coils. The flux produced by current in coils 22 and 22' is preferably of such a value as to normally prevent the flow of current through the tubes so that the current in the output circuits is substantially zero. Coils 25 and 25' of tubes 14 and 15, respectively, are connected differentially across a pair of line conductors 28 and 29. For driving electrons from the heated cathodes 16 and 16' to the anodes 20 and 20', a battery 27 is connected between these electrodes.

The type of vacuum tube employed in the present invention is controlled by current changes, being similar to that disclosed in

British Patent 167,561 of August 8, 1921, and since the vacuum tube per se does not form a part of the present invention, only so much of the apparatus has been shown as is considered necessary for clear understanding of the invention.

- The line conductors 28 and 29 extend from a distant station where they may terminate in the contacts of a transmitting key 30.
- 10 When the key 30 is in its normal position, or the position shown in the drawing, battery 31 is disconnected from the line conductors, and consequently no current flows in either the operating winding 13 or the magnetizing windings 9 and 10 of the relay structure. However, if key 30 is operated in a manner whereby conductor 28 is made positive while the conductor 29 is made negative, the field produced by coil 25 of the 20 vacuum tube structure 14 will neutralize that of coil 22 and allow current to flow from the filament or cathode 16 to the anode 20 of the vacuum tube 14 and thus through the magnetizing windings 9 and 10 in series.
- 25 When the polarity of the line is reversed, that is, the key 30 is operated to make the line conductor 28 negative and the line conductor 29 positive, the direction of the current in operating winding 13 will be 30 reversed, but coil 25' in this case will oppose the operation of coil 22' of the vacuum tube 15, thereby allowing current to flow through the magnetizing windings 9 and 10 in the same direction as before, but through 35 the other vacuum tube.

When current is allowed to flow through the magnetizing windings 9 and 10, the armature 11 will swing toward the pole piece 8 when a positive impulse is impressed on 40 the line conductors, and will swing in the opposite direction when a negative impulse is transmitted.

Although the invention has been illustrated in conjunction with a particular 45 circuit, it is obvious that changes may be made without departing from the scope of the appended claims.

The invention claimed is:

1. A signaling system comprising a transmission line, a magnetic winding connected 50 to said line, an electron discharge device operating substantially without gas ionization located in the magnetic field of said winding, said field serving to control the discharge of electrons in said device, an output circuit for said device and a receiving device in said output circuit responsive to current flowing therein.
2. In combination, an electron discharge 55 device comprising current carrying means for controlling the discharge therethrough, circuit connection for supplying current impulses to said current carrying means, an output circuit for said discharge device in 60 which uni-directional magnetizing currents

are generated, and a receiving device in said output circuit responsive to the current impulses in said circuit connections and the uni-directional magnetizing currents supplied through the operation of said electron 70 discharge device.

3. In a signaling system, a transmission line, a current carrying winding connected to said line for setting up a field of magnetic flux, a second winding for setting up a field 75 of flux, an electron discharge device located in said fields, the flux of said second field serving normally to prevent the discharge of electrons, said first field serving to overcome the second field to permit the discharge 80 of electrons, an output circuit for said device, and a receiving mechanism in said output circuit responsive to current flowing therein.

4. In combination, a source of electrical 85 impulses of opposite polarity, a pair of magnetically controlled electron discharge devices operating substantially without gas ionization, input circuits for each of said devices, circuit connections for connecting 90 said circuits differentially across said source, and an output circuit for each of said devices having a branch in which impulses are unidirectionally repeated.

5. In combination, a source of electrical 95 impulses of opposite polarity, a pair of magnetically controlled electron discharge devices operating substantially without gas ionization, an input circuit for each of said devices circuit connections connecting said 100 input circuits differentially across said source, a relay having operating and magnetizing windings, said operating winding being serially connected to said source and input circuits, while said magnetizing windings are associated with the output circuit of 105 said discharge devices, and circuit connections whereby uni-directional impulses are repeated from said discharge devices to said magnetizing windings.

6. In combination, a source of electrical 110 impulses of opposite polarity, a pair of vacuum tubes consisting of an evacuated envelope, a cathode and a cylindrical anode, provided with means for magnetically controlling the passage of electrons from the cathode to the anode, an input circuit for each of said tubes, circuit connections for connecting said input circuits differentially across said source, a relay having operating and magnetizing windings, said operating winding being serially connected with said source and the input circuits, while said magnetizing windings are associated with the output circuit of said vacuum tubes, and circuit connections whereby uni-directional impulses are repeated from said vacuum tubes to said magnetizing windings.

7. In a signaling system, a signaling circuit, a source of electrical impulses of op-

posite polarity associated with said signaling circuit, a pair of electron discharge devices operating substantially without gas ionization responsive to current changes in said signaling circuit, input circuits for each of said devices, circuit connections for connecting said input circuits differentially with respect to said signaling circuit, and

an output circuit for said devices having a branch in which uni-directional impulses ¹⁰ are repeated.

In witness whereof, I hereunto subscribe my name this 29th day of August, A. D., 1922.

HAROLD W. NICHOLS.
